ATTORNEY.

UNITED STATES PATENT OFFICE.

HARRY W. R. BLANCK, OF BALTIMORE, MARYLAND.

DESIGN FOR A FONT OF TYPE.

No. 37,716.

Specification for Design.

Patented Dec. 5, 1905.

Application filed September 30, 1905. Serial No. 280,844. Term of patent 7 years.

To all whom it may concern:

Be it known that I, HARRY W. R. BLANCK, a citizen of the United States, residing at Baltimore city, State of Maryland, have invented a new, original, and ornamental Design for a Font of Type, of which the following is a specification.

The accompanying drawing is a view showing a font of type embodying the design.

I claim—

The ornamental design for a font of type, as shown.

HARRY W. R. BLANCK.
